METHOD OF MAKING WELTING

William C. Vizard, Brockton, Mass., assignor, by
mesne assignments, to Barbour Welting Company,
Brockton, Mass., a copartnership composed of
Perley E. Barbour, Walter G. Barbour,
and Richard H. Barbour

Application September 30, 1932, Serial No. 635,570

6 Claims. (Cl. 12—146)

This invention relates to the manufacture of
welting, particularly of beaded welting used as
calking welt in Goodyear shoes, nailed shoes,
mock welts and the like.

5 Calking welt comprises a body flange for receiving
the stitching and an adjoining edge bead
the combined width of which is $\frac{1}{8}$ inch in the
most desirable commercial size. In the manu-
facture of types heretofore commercially avail-
able a strip $\frac{1}{8}$ inch wide has been required to
produce a $\frac{1}{8}$ inch calking welt. Saving of stock
is of great importance and any method by which
standard calking welt can be made starting with
a narrower strip of leather is eagerly sought for.

10 The object of this invention is to provide a
method of making calking welt of standard width
from a strip of leather only slightly wider, and to
the accomplishment thereof the steps for practis-
ing the method will be described in detail in con-
nection with accompanying drawing and the scope
20 of the invention will be set forth in the appended
claims.

In the drawing, all the figures being in perspec-
tive,

25 Figure 1 shows a strip of grain faced leather;
Figs. 2 and 3 show, respectively, the first
preparatory cutting of the strip and the result
thereof;

30 Figs. 4, 5 and 6 show the progressive forming up
steps to produce a calking welt from the cut blank
of Fig. 3, and

Fig. 7 shows the finished welt, molded and
trimmed.

35 In practising the new method, as illustrated by
the accompanying drawing, for the production of
 $\frac{1}{8}$ inch calking welt a strip 10 only $\frac{1}{8}$ inch wide
need be used. This may be leather having a
natural grain face or it may be a split having had
40 grain applied to one face as by cementing thereto
a grain ribbon obtained from finishing processes
in the manufacture of other kinds of welting, or
in other ways. In the following description and
claims "grain faced" is inclusive of either a
natural or an applied grain. The present method
45 depends on the formation of a U-shaped blank
from the grain faced strip before performing the
forming up steps. Accordingly a segment 12 is
cut from between the two faces of the strip 10
leaving a blank (Fig. 3) having a grain faced
50 wing 14 and a flesh wing 16 connected at one edge
by an uncut portion 18 of the original stock, this
portion being the flesh remaining after removing
the segment 12. At the time the segment 12 is
removed the flesh corner of the stock which be-
55 comes the wing connector 18 may be beveled as

at 19 to facilitate forming up as presently ex-
plained. It will be observed that the cut for re-
moving the segment 12 provides a chamfered inner
edge. This leaves an oblique face 20 on the con-
nector stock 18 which makes the flesh wing wider
than the grain faced wing the purpose of which
will be plain when the forming up of the blank
is described. Those skilled in the art will recog-
nize that the segment 12, although composed of
split leather, is of commercial value and is not 10
waste.

Having the U-shaped blank, it is formed up into
a calking welt as illustrated by Figs. 4 to 6. The
wings 14 and 16 are opened about the joiner
of the flesh wing 16 with the connector stock 18 15
as a hinge, this being the point where there is the
least connector stock to resist bending, until the
grain at the connected end at least, of the wing 14
stands at substantial right angles to the flesh
wing 16. This throws the original edge 22 of the
strip 10 into general alignment with the bottom
of the flesh wing 16 thus forming an extension
thereof. It also turns the connector stock 18 to
a position wherein its bevel 20 slopes upward and
outward from the said flesh wing 16. Cement 20
may be applied to the inner faces of the two wings
at any time after the wings have been opened
sufficiently to be contacted by a cement roll or
other applying device. Any satisfactory kind of
enduring cement may be used. The grain faced
wing 14 is now turned back toward the flesh
wing 16, the hinge being at the upper edge of the
bevel 20, and is pressed into contact with said
bevel and with the cemented face of the flesh
wing 16. It will be observed that the bevel at 19 35
assists in turning the connector stock to a position
where its edge 22 forms a part of the bottom of
the welt, and that the oblique face 20 provides for
a narrowed upper edge on the bead of the calking
welt. 40

The final step is the pressing and molding to
shape. In these operations the bead is round-
ed or otherwise shaped as desired and the pres-
sure is sufficient to form a substantially flat bot-
tom and to preserve the substantially square cor-
ner at the base of the bead. It is convenient,
during this step, to remove the string 24 which
is the excess width of the flesh wing after the
forming up operations have been performed.
An important advantage of this method of pro-
ducing calking welt accrues from selecting a
substantially triangular cross-section for the
connector stock 18 which supplies the body stock
for the edge bead. Heretofore the stock of the
bead body has been of rectangular cross-section 50
55

and, due to variations in the character of the leather along the length of the blank, it has sometimes been difficult to finish the bead to the desired shape, that is, with a sloping or even concaved back for fitting to the shoe stock which it contacts. The oblique face 20, which forms the rear face of the bead body, eliminates corners which must be molded down, provides an initial cross-section that approaches the final shape of the bead facilitating molding a narrow top edge, and presents a rear wall that may readily be shaped as desired.

The operations described, when performed, produce a calking welt having a firm and strong body for receiving stitches, a bead that is grain faced throughout its surface and a flesh bottom that will lie flat and cling to the underlying material of the shoe in which the welting is used.

Variations in the described steps used in the method of manufacture of the calking welt may be made without departing from the principles and scope of the invention as defined by the following claims.

Attention is called to applicant's co-pending application for cork sole welting and the like, Serial No. 533,993, filed April 30, 1931, in which will be found generic claims covering the cork welting herein disclosed and its method of manufacture. The claims of this application are confined to the novel method of making one-piece welting as disclosed herein and such equivalents as may be permitted by the prior art.

The nature and scope of the invention having been indicated and the preferred method of manufacture having been described, what is claimed as new, is:—

1. The method of making calking welt and the like which comprises removing a segment centrally from a strip of grain faced leather forming a U-shaped blank having a grain faced wing and a flesh wing connected at one edge by an uncut portion of the original stock, opening said wings about the line of joinder of the flesh wing to said connector stock, cementing their inner faces, turning the grain faced wing back upon said connector stock and upon said flesh wing forming an edge bead, and pressing and molding to shape.

2. The method of making calking welt accord-

ing to claim 1 in which the said segment has a chamfered inner edge leaving an oblique face on said connector stock between the two wings.

3. The method of making calking welt according to claim 1 in which the said segment has a chamfered inner edge leaving an oblique face on said connector stock between the two wings, said face, when said wings are opened, sloping upwardly and outwardly from said flesh wing.

4. The method of making calking welt and the like which comprises removing a segment having an inner chamfered edge centrally from a strip of grain face leather forming a U-shaped blank having a grain faced wing, a flesh wing wider than the grain faced wing and connector stock at one edge that is the flesh of the original strip, opening said blank by turning substantially 90° on the line of joinder of said flesh wing and the connector stock, cementing said wings, then folding said grain faced wing down upon the beveled face of said connector stock and into contact with said flesh wing forming a grain faced beaded edge, and molding the welting to shape.

5. The method of making calking welt and the like which comprises making parallel slits in one edge and part way across a strip of grain faced leather and removing the flesh stock between said slits leaving two wings connected at one edge by the remaining flesh stock, cementing the inner faces of said wings, and then rolling said connector stock outward and wrapping a portion of one of said wings about said connector stock to make a bead and securing the remainder of said wing to the other wing to make a body adjoining said bead.

6. The method of making calking welt and the like which comprises removing a segment centrally from a strip of grain faced leather forming a U-shaped blank having a grain faced wing and a flesh wing connected at one edge by an uncut portion of the original stock, opening and cementing the inner faces of said wings, rolling said connector stock outward to lie at the end of said flesh wing and to turn its grain covered face at substantial right angles to said flesh wing, laying the grain faced wing against said connector stock and the flesh wing, and pressing and molding to shape.

WILLIAM C. VIZARD.
